PASSENGER CAB FOR AMUSEMENT RIDE

Samuel P. Goforth and Joseph A. Goforth, Shelby, N.C., assignors to Goforth Brothers, Inc., Shelby, N.C.

Filed Mar. 17, 1971, Ser. No. 125,462

Term of patent 14 years

Int. Cl. D21—03

U.S. Cl. D34—5

FIG. 1 is a perspective view of the passenger cab for amusement ride looking slightly down at the top thereof; and

FIG. 2 is a side elevational view thereof on a reduced scale.

The other sides of the passenger cab for amusement ride are substantially the same as those shown in the figures of the drawings.

We claim:

The ornamental design of a passenger cab for amusement ride, substantially as shown and described.
